United States Patent Office

WALLACE T. MUNGER, OF BRANFORD, CONNECTICUT, ASSIGNOR TO
THOMAS KENNEDY, OF SAME PLACE.

Letters Patent No. 62,967, dated March 19, 1867.

IMPROVEMENT IN ATTACHING DOOR KNOBS TO THEIR SHANKS.

The Schedule referred to in these Letters Patent and making part of the same.

TO ALL WHOM IT MAY CONCERN:

Be it known that I, WALLACE T. MUNGER, of Branford, in the county of New Haven, and State of Connecticut, have invented a new Apparatus for Filling Knobs; and I do hereby declare the following, when taken in connection with the accompanying drawings and the letters of reference marked thereon, to be a full, clear, and exact description of the same, and which said drawings constitute part of this specification, and represent, in—

Figure 1, a side view; and in

Figure 2, a vertical central section.

My invention relates to an apparatus to facilitate the securing of metal necks to mineral or similar knobs, and consists in the arrangement of an apparatus arranged to receive the requisite quantity of filling material, and when so received to discharge the said requisite quantity into the knob, whereby the process is greatly facilitated.

To enable others skilled in the art to construct and use my improvement, I will proceed to describe the same as illustrated in the accompanying drawings.

A is a cylinder, connected by a pipe, B, with the vessel which holds the filling material, whether it be molten lead, sulphur, plaster, or other material in a plastic state. Into the said cylinder is closely fitted a plug, C, but so as to be turned freely therein by a handle, D, attached thereto. In one side of the said plug is formed a cavity, E, corresponding to the pipe B, and opening through the lower end of the plug by a channel, *a*. F is an adjusting spindle, which, by being raised up or down into the cavity E, increases or diminishes the capacity of the said cavity. The said spindle F has an opening through it and communicating with the cavity, (as denoted in fig. 2,) to permit the escape of air from the cavity when the filling substance is admitted thereto, and also to admit air to the cavity when the contents are discharged. In the lower end of the cylinder A is fixed a tube, I, corresponding in size to the opening in the neck of the knob, and in position so that when the plug C is turned so as to close the pipe B the channel *a* will open into the said tube, as denoted in red, fig. 2.

To fill a knob by my apparatus, place the neck N into the knob K, as seen in fig. 2, then set the neck on to the tube I, (the said tube being provided with a gauge, L, so that the tube will enter the neck the proper distance,) the pipe B conducting the filling substance into the cavity E, turn the plug C, (which cuts off the pipe E,) until the channel *a* opens into the tube I, the filling substance then passes into the knob around the neck; the knob is then removed for the substance to harden, and another knob placed thereon to be filled in like manner.

Having therefore thus fully described my invention, what I claim as new and useful, and desire to secure by Letters Patent, is—

1. The combination of the cylinder A and plug C and tube I, constructed and arranged so as to receive and discharge the requisite quantity of filling substance, substantially as herein set forth.
2. In combination with the above, I claim the adjusting spindle F, arranged to gauge the quantity of filling substance, substantially as herein set forth.

W. T. MUNGER.
